Primary Examiner — Derrick Holland*Assistant Examiner* — Lauren Calve(74) *Attorney, Agent, or Firm* — Muncy, Geissler, Olds & Lowe, P.C.(57) **CLAIM**

The ornamental design for a telescope, as shown and described.

DESCRIPTION

FIG. 1 is a perspective view of a telescope according to the present invention.

FIG. 2 is a front view of the telescope of FIG. 1.

FIG. 3 is a rear view of the telescope of FIG. 1.

FIG. 4 is a left view of the telescope of FIG. 1.

FIG. 5 is a right view of the telescope of FIG. 1.

FIG. 6 is a top view of the telescope of FIG. 1; and,

FIG. 7 is a bottom view of the telescope of FIG. 1.

The broken lines shown represent unclaimed subject matter and form no part of the claimed design.

1 Claim, 7 Drawing Sheets(56)
